ELECTRIC CORD-PLUG.

1,126,394.

Specification of Letters Patent.

Patented Jan. 26, 1915.

Application filed June 27, 1914. Serial No. 847,675.

To all whom it may concern:

Be it known that I, THOMAS F. CLARK, a citizen of the United States, and a resident of West Hoboken, in the county of Hudson 5 and State of New Jersey, have invented a new and Improved Electric Cord-Plug, of which the following is a full, clear, and exact description.

This invention relates to electric socket 10 plugs, and has to deal more particularly with detachable connectors whereby an electric light or other current consuming device can be readily attached to or detached from a lamp or wall socket or equivalent 15 means connected with an electric supply circuit.

The general objects of the present invention are to improve and simplify the construction of devices of the character referred 20 to so as to be reliable and efficient in use, comparatively simple and inexpensive to manufacture and so designed that electric connections can be easily made or broken.

A further object of the invention is the 25 provision of a novel form of circuit connector which is especially adapted for portable lights or other current consuming devices, whereby any longitudinal strain or pull on the cord conductor will not cause 30 the parts to become disconnected and broken or damaged.

In carrying out the invention the usual 35 attaching plug for lamp sockets and the like may be employed with the insulating base or porcelain part thereof made in two sections that are slidably connected by a relative movement transversely to the axis of the plug, the sections having interlocking parts which withstand a separating strain 40 coincident with the axis. The outer section is fixedly connected with the wires of the cord conductor and is provided with contacts which engage with contacts on the other section of the plug, one set of contacts 45 being spring so as to make good electrical connections with the other contacts. The threaded shell contact and the central contact are of usual construction so as to screw into a lamp socket, and these parts are electrically connected respectively with the contacts in the body of the plug with which the contacts on the detachable part or section normally engage. Thus, the plug is attached to a lamp socket in the usual man-

ner to derive current from a supply circuit, 55 but if the cord conductor is desired to be removed it is simply necessary to detach the removable section of the plug by a relative lateral movement while the body part of the plug remains in the lamp socket. 60

For a more complete understanding of the invention, reference is to be had to the accompanying drawing forming a part of this specification, in which similar characters of reference indicate corresponding 65 parts in all the views, and in which—

Figure 1 is a perspective view of the attaching plug; Fig. 2 is a perspective view of the removable section detached; Fig. 3 is a side view of the body section of the plug 70 with the removable section detached; Fig. 4 is a sectional view on the line 4—4, Fig. 3, with the removable section of the plug detached; and Fig. 5 is a similar view with the removable section attached. 75

Referring to the drawing, A designates the attaching plug and B the cord conductor through which current is supplied to a lamp or equivalent translating device. The invention is shown applied in the present instance to a lamp socket plug, but it is to be understood that it can be applied to other devices for obtaining a connection with the supply circuit. 80

The plug comprises a base section 1 and 85 an outer or removable section 2, which is detachable from the body or base section 1 by a relative lateral movement, or in a plane transverse to the axis of the plug. As shown in Fig. 2, this removable section is in 90 the form of a ring having a central opening 3 through which the wires of the cord conductor B extend. This ring 2 has a tongue or projection 4 provided with lateral wings or shoulders 5, so that it is approximately T-shaped 95 in cross-section, as shown in Fig. 1. On the inner face 6 of this tongue or projection are screws or equivalent means 7 which serve to hold the contacts 8 and 8' in place, and also to connect the wires 9 and 9' respectively 100 to such contacts. The contacts are strips of spring metal which are bent approximately transversely to the axis of the removable section 2, and they are normally sprung up from the top surface 10 of the projection 4. 105 A lip 11 is formed on the projection 4 at the outer surface thereof, and the free ends of the spring contacts 8 and 8' lie inwardly

from the said lip, so that the latter forms a protecting means or guard for the spring contacts.

The body 1 of the device is formed with 5 a chamber 12 which is open in the face 13 of the base 1 and in the peripheral face 14, and this chamber has inwardly-extending flanges 15 at opposite sides forming tongues which engage in grooves 16 in the 10 sides of the part 4 of the section 2. In other words, the two sections 1 and 2 have interlocking flanges 5 and 15 which extend transversely to the axis of the plug and thereby withstand any separating strain 15 applied in the line of the axis. In this chamber 12 are fixed contacts 17 and 17' which are engaged by the contacts 8 and 8' respectively. The contact 17 is secured in place by a screw or equivalent means 18 which forms an electrical connection between such contact and a threaded shell contact 19 on the plug, and the contact 17' is held in place by a screw or equivalent means 20 which also secures the central 25 contact 21 to the plug and electrically connects the contacts 17' and 21. Between the contacts 17 and 17' there is formed a partition or barrier 22 which is adapted to lie between the contacts 8 and 8' when the 30 two parts of the plug are assembled, so that there is no danger of short-circuiting between the contacts. This partition or baffle may be formed integral with the porcelain parts or base 1 of the plug.

35 From the foregoing description taken in connection with the accompanying drawing, the advantages of the construction and method of operation will be readily understood by those skilled in the art to which 40 the invention appertains, and while I have described the device which I now consider to be the best embodiment thereof, I desire to have it understood that the device shown is merely illustrative and that such changes 45 may be made when desired as are within the scope of the appended claims.

Having thus described my invention, I claim as new and desire to secure by Letters Patent:

50 1. A connector of the class described comprising a base section, a detachable section, conductors connected with the detachable section and subject to a strain tending to separate the sections, means for detachably connecting the sections by relative movement transversely to the line of strain, and contacts arranged on the respective sections to engage when the latter are assembled.

60 2. An electric connector comprising a base section, a removable section having an

opening, conductors extending into the opening and fastened to the removable section and subject to a strain tending to separate the sections, one of the sections having a chamber, a tongue on the other section to extend into the chamber, interlocking flanges on the walls of the chamber and sides of the tongue for permitting the sections to be connected or disconnected by 65 relative sliding movement transverse to the line of strain on the conductors, contacts on the removable section and to which the conductors are connected, and contacts on the other section to engage with the contacts 70 of the removable section when the sections are assembled.

3. An electric connector comprising two detachably-connected sections, one section having a chamber and the other a part extending into the chamber and provided with grooves, flanges in the chamber arranged to engage in the grooves of the said part, a partition in the chamber, contacts fastened in the chamber at opposite sides 85 of the partition, contacts on the said part and spaced from each other to lie at opposite sides of the partition and arranged to engage respectively the first-mentioned contacts, and conductors connected with the 90 contacts.

4. An electric socket plug, comprising a base section, a removable section having an opening, conductors extending into the opening, a tongue or extension on the removable section, contacts on the said tongue and connected with the respective conductors, a chamber in the base section and open in two faces thereof to receive the said tongue of the removable section, interlocking shoulders on the said tongue and in the chamber, whereby the sections are separable and connectible by relative lateral movement transverse to the axis of the plug, contacts in the chamber arranged to 100 be engaged respectively by the first-mentioned contacts, a shell contact on the base section, a conductor for connecting the shell contact with one of the contacts of the chamber, a central contact on the exterior 105 of the plug and concentric with the shell contact, and means for connecting the central contact with the other contact in the chamber.

In testimony whereof I have signed my 115 name to this specification in the presence of two subscribing witnesses.

THOMAS F. CLARK.
